(57) **CLAIM**

The ornamental design for a tampon applicator, as shown and described.

DESCRIPTION

FIG. 1 is a front elevation of a first embodiment of our new tampon applicator;

FIG. 2 is a rear elevation thereof, with a plunger of the tampon applicator shown in phantom and forming no part of the invention;

FIG. 3 is a right side elevation thereof;

FIG. 4 is a left side elevation thereof;

FIG. 5 is a top plan view thereof;

FIG. 6 is a bottom plan view thereof; and

FIG. 7 is a perspective view thereof;

FIG. 8 is a front elevation of a second embodiment of our new tampon applicator;

FIG. 9 is a rear elevation thereof, with a plunger of the tampon applicator shown in phantom and forming no part of the invention;

FIG. 10 is a right side elevation thereof;

FIG. 11 is a left side elevation thereof;

FIG. 12 is a top plan view thereof;

FIG. 13 is a bottom plan view thereof; and,

FIG. 14 is a perspective view thereof.

The broken lines of the plunger in the drawing figures are included for the purpose of illustrating an environmental that forms no part of the claimed design.
